COMB

Filed Oct. 2, 1940.

UNITED STATES PATENT OFFICE

2,270,529

COMB

Samuel Kirschenbaum, Brooklyn, N. Y.

Application October 2, 1940, Serial No. 359,407

19 Claims. (Cl. 132—13)

This invention relates generally to combs. More particularly, my invention relates to the class of combs shown and described in my co-pending application Serial No. 317,467, filed February 6, 1940, for Combs, and adapted to treat the hair or scalp by applying oils or other suitable liquids thereto during the combing action.

One of the objects of the present invention is to provide a novel comb of the class described, which shall possess certain novel and improved features of construction, representing an advance over the comb disclosed in my said co-pending application Serial No. 317,467.

Another object of my invention is to provide a comb construction of the class described, having improved means for directing the path of flow of oil from a reservoir to the teeth of the comb, and for controlling the speed of such flow.

Other objects of my invention will, in part, be obvious and in part hereinafter pointed out.

Certain features described but not claimed in this application are described and claimed in my co-pending application Serial No. 359,408, filed simultaneously herewith and in my co-pending application Serial No. 317,467, filed February 6, 1940, of which the present application is a continuation-in-part.

The invention accordingly, consists in the features of construction, combinations of elements, and arrangement of parts which will be exemplified in the constructions hereinafter described, and of which the scope of application will be indicated in the claims.

In the accompanying drawing, in which is shown one or more of the various possible embodiments of my invention;

Fig. 1 is a front elevational view, partly sectional, of a portion of a comb, constructed in accordance with my invention;

Fig. 2 is a cross-sectional view taken substantially on the line 2—2 of Fig. 1;

Fig. 3 is a front elevational view of a portion of a comb illustrating a modified form of my invention;

Fig. 4 is a rear elevational view thereof;

Fig. 5 is a cross-sectional view taken substantially on the line 5—5 of Fig. 3; and

Fig. 6 is an enlarged cross-sectional view taken substantially on the line 6—6 of Fig. 3.

Referring now in detail to the drawing, I have illustrated in Figs. 1 and 2 one form of my invention in which a comb 10 of conventional design is employed, which may have the usual type of teeth 11 relatively closely spaced and teeth 12

relatively widely spaced, the said teeth 11 and 12 being integral with and depending from a back 14.

In accordance with the present invention, I have provided certain selected teeth, in this case, alternate teeth 12a of the relatively widely spaced teeth 12, with a plurality of grooves 16 transversely disposed with respect to the length of the said teeth 12a. The said grooves 16 are spaced from each other, along the length of the teeth, beginning at a point adjacent the free ends of the teeth 12a and extending upwardly for any desired predetermined distance, such as, for example, that shown in Figs. 1 and 2.

On one surface of the back 14 of the comb, I provide a longitudinally extending main oil reservoir 20 the bottom wall 20a of which, is recessed below the surface of the said back 14.

A protective wall 21 raised above the surface 20 of the back 14, surrounds the upper side wall 21a, and the end side wall portion 21b of the reservoir 20 and tapers from the said end portion 21b inwardly and downwardly toward the surface of the back 14, and in the direction of the teeth. A lower raised ridge 22 completes the side wall surrounding the reservoir to prevent the oil from overflowing from the reservoir 20 to undesired surface portions, when the comb is tilted in any direction. The said ridge 22 instead of being formed in a straight line as the corresponding upper part of the wall 21 is so constructed and arranged as to form the reservoir 20 into substantially three sectors A, B and C into which the oil will be separated to thus avoid too large a congregation of oil at one part of the reservoir when the comb is tilted.

It is noted that the reservoir 20 is open at the top to the surrounding atmosphere to insure the flow therefrom in the manner soon to be explained.

To hold the supply of oil in the reservoir 20, the bottom wall 20a thereof, is provided with a chain of interconnected grooves 25. It is noted that the said grooves 25 are of such width that the oil in the reservoir 20 will be held therein by capillary attraction. Any suitable arrangement of the grooves 25 may be employed, such as for example, that shown in the drawing, which I have found to have given satisfactory results.

Adjacent the ridge 22 and in the bottom wall of the reservoir 20, I provide a groove 23 deeper than the grooves 25 and so arranged that the oil from the grooves 25 will flow into the groove 23.

To direct the flow of oil from the reservoir 20

to the teeth 12a, I provide the following construction.

Communicating with the sections A, B and C of the reservoir 20, and with the groove portions 23 adjacent thereto, I provide grooves 26, 27 and 28 respectively. The central vertically disposed groove 26 also communicates with a lower horizontally disposed groove 29 which, in turn, communicates with a pair of horizontally disposed grooves 30 and 31, positioned slightly below the groove 29. The groove 27 leading from the sector B communicates with the groove 30, while the groove 28 leading from the sector C communicates with the groove 31. Each tooth 12a is provided with a groove 33 running along the length thereof, and terminating at a point on the tooth near the uppermost transverse groove 16, and communicating at the upper end with the grooves 30 and 31 as shown in Fig. 1 of the drawings.

It is thus seen from the above described construction that oil from the reservoir 20 will flow down the chain of grooves 25 just described into the groove 23 and into the grooves 33 to subsequently flow down the outer surface of the teeth 12a, to be drawn off by the hair during the combing action.

The grooves 26, 27 and 28 are disposed within and below recessed areas 35, 36 and 37 respectively.

Similarly the grooves 29, 30 and 31 are surrounded by recessed areas 38, 39 and 40 respectively communicating with the said recessed areas 35, 36 and 37 as shown. Each groove 33 of the teeth 12a is disposed within recessed areas 41, the said recessed areas 41 communicating directly with the recessed areas 39 and 40.

By surrounding all the oil carrying grooves 26 to 31 and 33 with recessed areas as above described, any overflow of oil from the said grooves will enter the said recessed areas and thus be prevented from spreading to undesired surfaces of the comb. It is also noted that due to the fact that the oil carrying grooves are disposed below the recessed areas which are, in turn, disposed below the surface of the comb, any loose hairs which might normally be picked up by the comb during the combing operation will be prevented from pulling oil from the grooves to flow along the hair to be deposited on undesired surface portions of the comb.

As a further precaution against undesired overflow of the oil from the grooves 29, 30 and 31, or from the recesses surrounding the same, I provide the following construction.

Disposed below the groove 29 and recessed area 38 surrounding the same, is a recessed area 45 communicating with the recessed areas 39 and 40, and surrounding an oil pocket 46. The recessed area 45 also communicates with the recessed area 38, and with a recessed area 48 surrounding a groove 47 in a tooth 12b in alignment with the said pocket 46. It is noted that the groove 47 communicates with the pocket 46 and that the tooth 12b is also provided with transverse grooves 16 similar to those provided in the teeth 12a. It is therefore seen that should there be an overflow of oil from the groove 26 or from the recess 38 or from the recesses 39 or 40, the oil will run into the pocket 46 and after filling the same, will flow down the groove 47 and on the surface of the emergency tooth 12b to be effectively transferred to the hair.

Similarly, in order to take care of any possible overflow when the comb is held vertically with

the sector C of the reservoir 20 lowermost, the recessed area 40 is extended to terminate in an enlarged area 49 having a pocket 50 therein, the said pocket 50 communicating with a groove 51 in a recessed area 52 of a tooth 12c similar in construction to the teeth 12a and 12b.

Should the comb be held with the sector B of the reservoir 20 lowermost, I provide an enlarged area 53 forming an extension of the recessed area 39 and having a pocket 54 therein. The said pocket 54 communicates with a groove 55 in a recessed area 56 of a tooth 12d similar in construction to the teeth 12a, 12b and 12c.

I have found that, in accordance with my invention, satisfactory results are obtained when I so construct that portion of the back 14 of the comb that it is backwardly angularly disposed with respect to the remainder of the back of the comb, as clearly shown in Fig. 2 of the drawing. 15 By such construction, when oil is supplied to the reservoir 20, while the comb is lying flat on its side, the oil from the reservoir 20 will start to flow into the chain of grooves and down the teeth so that when the comb is picked up for combing use, it will be in readiness to transfer oil to the hair.

It is well known that combs are generally made of materials such as hard rubber or the like, which are capable of generating static electricity

30 when used for combing, due to the frictional contact with the hair. I have also discovered that the static electricity thus generated is effective for aiding the oil film in passing from the teeth of the comb to the hair. In accordance with my invention therefore, the comb teeth 12a, 12b, 12c and 12d have been so constructed and arranged as above described, to take full advantage of the static electricity generated by the comb. However, to prevent the generated static electricity from acting upon the oil in the reservoir 20 to be drawn out therefrom to undesired parts of the comb, I provide a metallic strip 60 which may be imbedded in the material of the comb and which is designed to project outwardly from the back 14 thereof, so that it will be in direct contact with the fingers or the hand of the user of the comb. The metallic strip 60 will thus discharge the generated static electricity from the area of the reservoir 20.

50 In Figs. 3, 4 and 5 I have shown a modified form of my invention in which I employ the same conventional type of comb as shown and described in connection with the Figs. 1 and 2 form of my invention, namely the back 14' and the teeth 12'.

55 However, instead of the reservoir 20, I provide on the front surface of the comb, a reservoir 70 of a different type. This reservoir 70 comprises a main oil reservoir 71 open at the top to the atmosphere and of a predetermined depth and a plurality of auxiliary reservoirs 72 also open at the top to the surrounding atmosphere and disposed below the main reservoir 71. It is noted that the walls 72a surrounding the reservoirs 72 extend upwardly to a point below the level of walls 71a of the main reservoir 71, but that the bottom wall 71b of the main reservoir 71 and the bottom wall 72b of the auxiliary reservoirs 72 are substantially at the same level, thus forming a recessed area 73 surrounding the reservoirs 72. Between the lower horizontal portion of the wall 71a of the main reservoir 71 and the adjacent portions of the walls 72a of the reservoirs 72 I provide a channel 73 having a bottom wall 73b of the same depth as the bottom walls 71b and 72b.

Each auxiliary reservoir 72 communicates with the channel 73 by a relatively narrow opening 74, while the lower horizontal portions of the wall 71a adjacent the channel 73 is provided with a plurality of spaced slits or openings 75 forming points of communication between the reservoir 71 and the channel 73.

A raised wall 110 at each end of the recessed area surrounding the reservoirs 72 protects possible overflow of oil when the comb is turned. It is thus seen that the oil from the main reservoir 71 will flow into the channel 73 through the slits 75 and from the channel 73 to the auxiliary reservoirs 72 through the openings 74.

It is noted that each reservoir 72 is in alignment with a selected tooth 76 or 77 and that on opposite sides of each tooth 77 there is a tooth 78 of different construction from that of the teeth 76 and 77.

Each of the teeth 76 and 77 are provided on the front surface thereof with a recessed portion 79 running along the length of the teeth to a point spaced from the free ends thereof. In these recessed portions 79 I provide a groove 80 running lengthwise of the teeth as shown. In each tooth 76 the groove 80 runs upwardly to and communicates directly with a corresponding auxiliary reservoir 72, so that the oil from the main reservoir 71, which has filled the auxiliary reservoir 72 will flow down the front surface of the said teeth 76.

If desired transverse grooves 81 spaced from each other along the groove 80 may also be provided on the front surfaces of all the teeth 76 and 77 to retard the too rapid flow of oil down the said teeth.

Disposed below the reservoirs 72 and in alignment therewith and with each tooth 77 is a through aperture comprising the part 82 on the front surface of the comb and a part 83 on the rear surface of the comb, the said parts 82 and 83 being interconnected by a capillary neck 84 with the rear part 83 being disposed slightly below the front part 82. Each front aperture part 82 is provided with a surrounding recessed area or oil pocket 85, while the rear aperture part 83 is surrounded with a similar recessed area or oil pocket 86 on the rear surface of the comb. The front recessed areas 85 are each connected to the groove 80 of the corresponding tooth 77 and with the corresponding auxiliary reservoir 72 by a groove 88. It is also noted that a horizontally disposed groove 89 interconnects the pockets 85 with the grooves 80 of the teeth 76 and that the said groove 89 is surrounded by the same recessed area 101 as the reservoirs 72.

At the rear surface of the comb, as shown in Fig. 4, each opening part 83 communicates directly with a vertically disposed groove 87, which in turn interconnects with a horizontally disposed groove 108. The rear surfaces of each of the teeth 78 are provided with an arrangement of vertically and horizontally disposed grooves 109 and 90 set in recessed areas 91, similar to the grooves 80 and 81 on the front surfaces of the teeth 76. Each pair of grooves 109 communicates directly with a corresponding horizontal groove 108, the said groove 108 being provided with surrounding recessed areas 100 to take care of possible overflow of oil from the said grooves 108.

It is noted that the portion of the back 14' of the comb in which the reservoirs 71 and 72 are disposed may be tilted backwardly as shown in Fig. 5 of the drawing for the same purpose and function as that described in connection with the

tilting of the back 14 in the Figs. 1 and 2 from my invention.

It is thus seen from the above described construction that when a desired supply of oil is placed in the main reservoir 71 oil will be delivered down the front surfaces of a selected set of teeth and at the same time the said oil will also be directed to and down the rear surfaces of a second alternate group of selected teeth. In this way oil may be applied to all areas of the hair during the normal combing action.

It will thus be seen that there is provided a device in which the several objects of this invention are achieved and which is well adapted to meet the conditions of practical use.

As various possible embodiments might be made of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. In a comb of the class described having teeth and a back, the combination of a recessed area in said back forming a reservoir for receiving oil, said reservoir having bottom and side walls and being substantially entirely open at the top to the surrounding atmosphere, a plurality of grooves in said bottom wall designed to hold oil in said reservoir and means for directing the flow of oil from said reservoir to selected teeth.

2. A comb according to claim 1 in which the said grooves in the bottom wall of said reservoir are relatively narrow and are angularly arranged with respect to each other whereby to retard the flow of oil from the reservoir to said teeth.

3. In a comb of the class described having teeth and a back, the combination of a recessed area in said back forming a reservoir for receiving oil, said reservoir having bottom and side walls and being substantially entirely open at the top to the surrounding atmosphere, a plurality of grooves in said bottom wall designed to hold oil in said reservoir and means for directing the flow of oil from said reservoir to selected teeth, said last named means comprising a groove interconnecting said reservoir with said selected teeth.

4. A comb according to claim 3 in which the said groove interconnecting said reservoir with said selected teeth is formed in a recessed area to catch the overflow of oil from said groove and to prevent the same from spreading over undesired surfaces of the comb.

5. In a comb of the class described having teeth and a back, the combination of a longitudinal recessed area in one surface of said back forming a reservoir for receiving oil, said reservoir having bottom and side walls and being substantially open at the top to the surrounding atmosphere and being so shaped as to provide a plurality of reservoir sectors into which the oil in the reservoir will be distributed, a plurality of grooves in said bottom wall designed to hold the oil therein, and means for directing the flow of oil from said reservoir to selected teeth, said last named means comprising grooves communicating at one of their ends with each reservoir sector.

6. A comb according to claim 5 in which the said grooves are formed in recessed areas adapted to catch the overflow of oil therefrom and to

prevent the same from spreading over undesired surfaces of the comb.

7. A comb according to claim 1 in which that portion of said back, in which the said reservoir is formed, is angularly tilted backwardly with respect to the plane of the comb, for the purposes set forth.

8. A comb according to claim 1 in which that portion of said back, in which the said reservoir is formed, is angularly tilted backwardly with respect to the plane of the comb, for the purposes set forth and in which the bottom wall of said reservoir is angularly tilted away from the direction of the teeth for the purposes set forth.

9. In a comb of the class described having teeth and a back, made of rubber or similar material capable of generating static electricity, wherein an oil reservoir is provided and in which means are employed for directing the flow of oil from said reservoir to said teeth to be ultimately transmitted to the hair or scalp of the user during the combing action—that improvement which comprises providing a strip of electrically conductive material, so positioned as to normally come into contact with the hand of the user to thereby discharge the static electricity which is generated during the combing action.

10. In a comb of the class described having teeth and a back, the combination of an elongated recessed area in one surface of said comb and disposed in said back, forming a main reservoir for receiving oil therein, said main reservoir being completely open at the top to the surrounding atmosphere, a plurality of spaced auxiliary reservoirs disposed below said main reservoir, and certain selected teeth having grooves therein running lengthwise of the said teeth, said auxiliary reservoirs communicating with said main reservoir and with said grooves.

11. In a comb of the class described the combination according to claim 10 in which means are provided for transferring oil from certain of said auxiliary reservoirs to the opposite surface of said comb from that of said reservoirs and means for directing the flow of said transferred oil down selected teeth.

12. In a comb having teeth and a back and which is designed to treat the hair or scalp with oil or the like during the combing action, the combination of a recessed area in one surface of said comb forming a reservoir for receiving oil therein, and means for directing the flow of oil from said reservoir to the opposite surface of said comb.

13. In a comb having teeth and a back and which is designed to treat the hair or scalp with oil or the like during the combing action, the combination of a recessed area in one surface of said comb forming a reservoir for receiving oil therein, means for directing the flow of oil from said reservoir to the opposite surface of said comb and means for directing the flow of oil from said opposite surface of said comb down selected teeth.

14. In a comb having teeth and a back and

which is designed to treat the hair or scalp with oil or the like during the combing action, the combination of a recessed area in one surface of said comb forming a reservoir for receiving oil therein, and means for directing the flow of oil from said reservoir to the opposite surface of said comb, said last named means comprising a through aperture in said comb disposed below said reservoir.

15. In a comb having teeth and a back and which is designed to treat the hair or scalp with oil or the like during the combing action, the combination of a recessed area in one surface of said comb forming a reservoir for receiving oil therein, and means for directing the flow of oil from said reservoir to the opposite surface of said comb, said last named means comprising a through aperture in said comb disposed below said reservoir, said aperture comprising a pair of relatively wide portions on opposite sides of the comb interconnected by and communicating with a relatively narrow portion.

16. In a comb having teeth and a back and which is designed to treat the hair or scalp with oil or the like during the combing action, the combination of a recessed area in one surface of said comb forming a reservoir for receiving oil therein, and means for directing the flow of oil from said reservoir to the opposite surface of said comb, said last named means comprising a through aperture in said comb disposed below said reservoir, said aperture comprising a pair of relatively wide portions on opposite sides of the comb interconnected by and communicating with a relatively narrow portion, said relatively wide aperture portions being at different levels with respect to said reservoir.

17. In a comb of the class described having teeth and a back, the combination of a recessed area in said back forming a main reservoir for receiving oil, said reservoir having bottom and side walls and being entirely open at the top to the surrounding atmosphere, oil carrying grooves on the outer surfaces of said teeth, a first oil passageway communicating with said main reservoir and a second oil passageway interconnecting said first passageway with said grooves.

18. In a comb of the class described having teeth and a back, the combination according to claim 17 in which the said second oil passageway is substantially at a right angle to the axes of said teeth.

19. In a comb of the class described having teeth and a back, the combination of an elongated recessed area in said back forming a main reservoir for receiving oil, said reservoir having bottom and side walls and being entirely open at the top to the surrounding atmosphere, oil carrying grooves on the outer surfaces of said teeth, a plurality of oil passageways communicating with said reservoir, and a second plurality of oil passageways interconnecting said first plurality of oil passageways with said grooves.
